UNITED STATES PATENT OFFICE.

ABRAHAM K. L. BLACK, OF SUNNYSIDE, WASHINGTON.

MUSIC-LEAF TURNER.

1,006,904.

Specification of Letters Patent. Patented Oct. 24, 1911.

Application filed June 1, 1910. Serial No. 564,360.

To all whom it may concern:

Be it known that I, ABRAHAM K. L. BLACK, a citizen of the United States, residing at Sunnyside, in the county of Yakima 5 and State of Washington, have invented new and useful Improvements in Music-Leaf Turners, of which the following is a specification.

This invention relates to improvements in 10 music leaf turners and has for one of its objects the provision of a device of that kind adapted to be applied to the rack of a piano, organ or analogous musical instrument, and when so applied to present a neat and 15 attractive appearance.

Another object is the provision of a music 20 leaf turner including a pair of relatively movable push-rods connected with the leaf turner, the construction being such that by alternately pressing said push-rods the leaf turner will be moved in opposite directions.

With these and other objects in view, which will more fully hereinafter appear, the present invention consists in certain 25 novel details of construction and arrangement of parts, hereinafter fully described, illustrated in the accompanying drawings, and more particularly pointed out in the appended claim; it being understood that various changes in the form, proportion, size, and minor details of the device may be made, within the scope of the appended claim, without departing from the spirit or sacrificing any of the advantages of the invention.

In the accompanying drawings forming part of the specification; Figure 1 is a front elevation of a music rack provided with my improved device. Fig. 2 is a rear elevation thereof. Fig. 3 is a sectional plan view approximately on the line 3—3 of Fig. 2. Fig. 4 is a bottom plan view. Fig. 5 is a sectional end view on the line 5—5 of Fig. 2.

Similar numerals of reference are employed to designate corresponding parts throughout.

The rack is designated by the numeral 5 and adjacent to its opposite ends is provided with clips 6 and 7, said clips being each 50 preferably formed of a single piece of steel wire the opposite end portions of which are bent laterally and inserted into the outer face of the rack, and when so inserted a space will exist between the body of the clip and face of the rack sufficient to receive the covers of a music sheet or book when the

said music sheet or book is open. A clip 8 is positioned at the middle of the rack and is formed similar to the clips 6 and 7, and is designed to bear on the middle of an open 60 music book and coöperating with the end clips to prevent displacement of the said book. Extending inwardly from the medial portion of the upper side of the rack is an opening, the lower end of which terminates in a longitudinal slot or opening 9 positioned adjacent to the lower side of the rack. Loosely fitted in the said opening is a shaft 10, the lower end of which is journaled in an opening in the middle portion of 70 the lower side wall of the slot 9.

A leaf turning frame is in the present instance shown to be formed of a single piece of wire bent into a U-shape the opposite limbs of which are designated by the numerals 11 and 12. The upper of these limbs is provided at one end with a flattened head 13, having a central opening to snugly receive the upper end of the shaft 10. The lower limb 12 is terminally provided with a 80 divided head 14, between the sides of which is fixedly secured a pinion 15. The divided head 14 and pinion 15 are arranged in the oblong slot 9, the said head and pinion being provided with alining openings to 85 snugly receive the lower end portion of the shaft 10. With this construction it will be manifest when the shaft 10 is turned the leaf turner will be turned likewise.

While I have shown but one leaf turner 90 and a mechanism for operating the same, it must be understood, however, that I am not to be limited to this specific number, since it will be readily understood, from what will appear later, how a greater number of leaf 95 turners and parts for operating the same, may be employed without departing from the spirit, or sacrificing any of the advantages of the invention.

By reference now to Fig. 2 it will be seen 100 that arranged on the inner or rear face of the rack 5 is a frame, the opposite longitudinal sides of which extend longitudinally of the rack and are designated by the numerals 16 and 17. The sides 16 and 17 are 105 arranged beyond the opposite sides of the slot 9 their opposite ends being connected together by the end pieces 18 and 19. Positioned between the sides 16 and 17 and at the opposite ends of the slot 9 are plates 20 110 and 21 extending at right angles to the inner or rear face of the rack 5 and corre-

sponding in length, approximately to the distance between the opposed inner faces of the sides 16 and 17. The medial portions of the plates 20 and 21 are provided with ob-
5 long openings, the said openings being in alinement with the medial line of the slot 9. Slidingly fitted in the openings are the opposite end portions of an operating rack bar 22, the teeth of which are presented out-
10 wardly and mesh with the teeth of the pinion 15. By reference now to the drawings it will be seen that guide openings are formed in the end pieces 18 and 19 and in alinement with the rack bar 22, and slid-
15 ingly fitted in these guide openings are the outer ends of connecting rods 23 and 24, the inner ends of which are loosely connected to the opposite ends of the rack bar 22. Jour-
20 naled adjacent to the opposite ends of the sides 16 and 17, and adjacent to the outer surfaces of said sides are shafts 25 and 26. The medial portions of these shafts are pro-
25 vided with crank arms 27 and 28, the said crank arms 27 and 28 extending at right angles to the medial portions of the shaft and having at their free ends inwardly ex-
30 tends slots which receive lateral studs 29 and 30, extending from the medial portions of the connecting rods 23 and 24. The lower
35 ends of the shafts 25 and 26 extend below the lower surface of the lower side 17 of the frame and have fixedly secured thereto crank arms 31 and 32, said crank arms 31 and 32 being positioned on the shafts 25 and 26 at approximately 270° from the
40 crank arms 27 and 28. The crank arms 31 and 32 extend approximately in length to the crank arms 27 and 28 and extend to points midway between the shafts 25 and 26 and center of the lower side 17 of the frame, and adjacent to their terminals are provided with outwardly extending crank pins 33 and 34. A pair of links are designated by the numerals 35 and 36, the inner ends of said
45 links being provided with openings for the reception of a pivot pin 38, extending through the center of the lower side 17 of the frame. The outer ends of the links are provided with longitudinal slots 38 and 39, which receive the cranks pins 33 and 34, as clearly shown in the drawings. Formed in the rack 5 and adjacent to the lower side thereof are a pair of spaced openings in

alinement, with the medial portions of the links 35 and 36, and slidingly fitted in these openings are push-rods 40 and 41, the inner ends of which are pivoted to the medial portions of the links 35 and 36 and the outer ends of which are provided with buttons 42 and 43. With this construction it will be manifest when the parts are positioned as shown in the drawings and the leaf turner is on the left of the rack, that by forcing the push-rod to the right inwardly, will result in rocking the shafts 25 and 26, whereby the opposite push-rod will move outwardly and at the same time the rack bar will be reciprocated, thus turning the leaf turner to the opposite side of the rack. It will be manifest when the parts are in this position and it is desired to turn the leaf to its original position the same can be done by depressing the push-rod on the left, whereupon the parts will resume their original positions. 75

From the foregoing, it is evident that I have provided a device which is comparatively simple in structure and inexpensive in manufacture, embodying few parts and these so arranged that the danger of derangement will be reduced to a minimum. 80

I claim:—

In a music leaf turner, the combination with a frame, and a leaf turning device; of a horizontally reciprocating rack bar, a pinion connected with the leaf turning device and engaging the rack, connecting rods slidingly fitted in the frame and connected each at one end to the rack bar, a pair of oppositely disposed vertical shafts jour- 85 naled in the frame, crank arms at the upper and lower ends of said shafts, the upper of said crank arms being connected at one end to the said connecting rods, a pair of links pivoted at one end to the frame and 90 pivotally connected at their opposite ends to the lower of said crank arms, and a pair of relatively movable reciprocating push rods connected to the links. 95

In testimony whereof I affix my signature in presence of two witnesses. 100
